W. W. Shaw

UNITED STATES PATENT OFFICE.

WILLIAM, W. SHAW, OF TROY, NEW YORK.

RUBBER HEAD FOR LEAD-PENCILS.

Specification forming part of Letters Patent No. 23,504, dated April 5, 1859; Reissued June 24, 1862, No. 1,319.

To all whom it may concern:

Be it known that I, Wm. W. SHAW, of Troy, in the county of Rensselaer and State of New York, have invented a new and Improved Head for Lead-Pencils, Ink-Erasers, &c.; and I do hereby declare that the following is a full, clear, and exact description of the same, reference being had to the accompanying drawings, in which—

10 Figure 1, represents a vertical central section of the head which I attach to the top of pencils, etc. Fig. 2, is a vertical central section of another form of the same, and Figs. 3 and 4, are side elevations of pencils 15 with one of these heads attached to them.

Similar letters of reference in the several views refer to corresponding parts of my invention.

To enable other persons to understand 20 and use my invention I will proceed to describe it.

A represents a piece of india rubber, the shape of which may be such as represented in Fig. 1, or which may have a form as represented in Fig. 2, or any other form convenient for the purpose. I prefer however the form represented in the Figs. 1, or 2, as they give a good chance to reach to any mark or to any special point on the paper.

At the same time the round form is the most 30 convenient, as it can be used on all sides with equal advantage and as its bulk can thus be taken sufficiently large so as to make it last a certain time without being used up. This piece of india rubber A, is provided 35 with a socket B, the diameter of which corresponds to the size of ordinary pencils and which is just large enough and deep enough to fit tightly on the top of the pencil. In order to secure the same permanently to the 40 pencil some sort of a cement may be used such as gum arabic, glue, &c. I have adopted this method of attaching the india rubber heads as it thus is not necessary to alter the size of the pencils to conform to the 45 sockets in the heads, and the heads are easily molded with the sockets to suit to the size of the pencils which as is well known, are generally manufactured of a uniform size.

Having described my invention I claim 50 as an improved article of manufacture:

A head A, for lead pencils made of rubber in the manner herein shown and described.

WM. W. SHAW.
